STARTING MECHANISM FOR LAPPING MACHINES

Christian A. Hutto, West Columbia, S. C.

Application June 3, 1940, Serial No. 338,592

4 Claims. (Cl. 19—162)

My invention relates to improvements in starting mechanism for picker lapping machines and the principal object in view is to provide simply constructed means for automatically starting such machines, and which may be applied to lapping machines of commerce without necessitating material change in the basic construction thereof and which is quick acting and durable and inexpensive to manufacture and install.

To the accomplishment of the above, and subordinate objects presently appearing, a preferred embodiment of my invention has been illustrated in the accompanying drawings, set forth in detail in the succeeding description, and defined in the claims appended hereto.

In said drawings:

Figure 1 is a fragmentary view in side elevation of the preferred embodiment of my invention,

Figure 2 is a fragmentary view in front elevation illustrating the trip lever in tripped position,

Figure 3 is a similar view illustrating the trip lever in effective position,

Figure 4 is a view in perspective of the starting mechanism detached,

Figure 5 is a view in perspective of the stud bolt, and

Figure 6 is a view in perspective of the block.

Referring to the drawings by numerals, the starting mechanism of my invention is designed as equipment for a well-known type of picker lapping machine illustrated conventionally in the drawings, 1 designating one of the side frames, 2 a lap guard and 3 one of the usual lap pins which when empty is supported at opposite ends by concave seats, as at 4, forming forward elevated extensions of said guards. These machines are provided with a starting lever 5 extending horizontally, forwardly alongside the side frame 1 and pivotally mounted at the rear end thereof, as at 6, for rocking movement upwardly and downwardly to mesh and disengage, respectively, a suitably driven gear 7 thereon with a gear 8 operating mechanism for running stock to a rotating calender roll 9. Adjacent to the front end of the machine is an upstanding manually operative trip lever 10 pivoted at its lower end, as at 11', to a vertically slotted guide bracket 11 fixed to said frame 1 for the extension of the front end of said lever 5 therethrough, the trip lever being swingable laterally of said frame 1 in opposite directions into and from tripping position, respectively, relative to starting lever 5. In the tripping position of said lever 10, the

starting lever 5 is free to drop, under the influence of gravity, and disengage gears 7 and 8 and thereby stop said operating mechanism, not shown. Movement of said trip lever 10 from tripping position interposes a shoulder 12 thereon beneath the starting lever 5 to hold the latter in upswung position, the gears 7 and 8 meshed, and said operating mechanism running. The trip lever 10 is counterweighted at its lower end, as at 13, to swing from tripping position. The parts 14 and 15 are elements of the said operating mechanism which need merely be identified in passing.

According to my invention, the following mechanism is provided for elevating the starting lever 5.

Mounted in bracket bearings 16 on the front ends of the side frame bar 1, for vertical endwise movement is a slide bar 17 having a yoke 18 at its upper end similar to seat 4 and adapted to seat one end of the lap pins 3 when deposited in said seat 4. The bar 17 has a right angled, out-turned extension 19 at its lower end overlying a laterally extending arm 20 of a bell crank lever 21 pivoted for vertical rocking movement on a stud bolt 22 extending from said side frame 1 above the forward end of the starting lever 5, said bolt having a cotter pin 23 therein for retaining said bell crank thereon. The other and upstanding arm 24 of the bell crank 21 has pivoted thereto, as at 25, one end of a link 26 extending rearwardly therefrom, the other end of said link being pivoted, as at 27, to the upper portion of an upstanding lifter lever 28 arising from the starting lever 5 and having its lower end pivoted thereto, as at 28', so that said lever 28 is swingable on the lever 5. The upper end of lifter lever 28 has the form of a hook 29 designed under swinging of said lever 28 in opposite directions to be moved into and from overlying relation to a substantially rectangular block 30, suitably secured, as by bolts 31, to the journal 32 of the calender roll 9. As best shown in Figure 1, the block 30 is secured to said journal 32 concentrically thereof so that when the hook 29 is moved over the same either end of said block will pick up the hook and thereby elevate said lifter lever 28 and consequently the starting lever 5.

A coil spring 32 having its ends suitably connected to the lifter lever 28 and the starting lever 5, as at 33, 34, acts normally to swing said lever 28 in a direction to move said hook 29 from over the block 30 and hold said lever in a normal ineffective position. In this position of lifter lever 28, the bell crank 21 is positioned through the

medium of link 26 so that arm 20 thereof holds the bar 17 in an elevated position and the yoke 18 slightly above the seat 4. The numeral 36 designates a countersink in the lifter lever for accommodating a bar 35 which is a part of a knock-off mechanism of the machine and which forms no part of the invention. A plurality of apertures 37 in the link 26 provides for changing the pivotal connection thereof to arm 24 of bell crank 21 as occasion may require, for instance, to take up wear on the parts.

Referring now to the operation of the invention, when the lap pin, or rod 3 is empty, or in other words, when the finished lap is removed therefrom, the pin is placed over the seats 4 with one end resting in yoke 18. The weight of the pin in yoke 18 lowers rod 17 in guides 16. Such lowering of rod 16 rocks the bell crank 21 in the proper direction, counterclockwise as viewed in Figure 1, to move the link 26 so that the latter swings the lifter lever 28 in a direction to move the hook 29 over the block 30. As will be obvious, if the starting lever 5 is down, in gear disengaging position, said hook 18 is thereby positioned down over the block 30 for operation by the latter so that rotation of the calender roll 9 and block 30 elevates the lifter lever 28, and hence the starting lever 5, to throw the machine in gear and set in motion said operating mechanism. As has already been set forth, the trip lever 10 holds the starting lever 5 elevated until operated manually to tripping position to stop the drive. As will also be obvious, when the lap pin 3 is removed from the yoke 18, bar 17, bell crank 21, link 26 and lifter lever 28 will be returned to normal position, shown in Figure 1, by the spring 32, and as soon as the starting lever 3 has been lowered following upon operation of the trip lever 10 from tripping position.

By starting the machine in this manner, the operator is enabled to remove and weigh the finished lap while the proper amount of stock is run through the machine to start a new lap. Obviously, in thus starting the machine without stopping running of the stock through, while removing and weighing the finished lap, much time is saved and production speeded up.

The foregoing will, it is believed, suffice to impart a clear understanding of my invention without further explanation.

Manifestly the invention, as described, is susceptible of modification without departing from the inventive concept, and right is herein reserved to such modifications as fall within the scope of the subjoined claims.

Having described the invention, what I claim as new is:

1. In a picker lapping machine, the combination with a vertically swingable starting lever for operating mechanism, a constantly rotating calender roll, and a lap pin, of means to lift said starting lever comprising a lifting lever pivoted to said starting lever for setting in opposite directions into and from effective positions, respectively, and endwise movable in the effective position thereof to lift said starting lever, means operative by the weight of the lap pin thereon to

set said lifting lever in effective position, and means on said calender roll operative under rotation of the latter to move said lifting lever in the effective position of said lever.

5 2. In a picker lapping machine, the combination with a vertically swingable starting lever for operating mechanism, a constantly rotating calender roll, and a lap pin, of means to lift said starting lever comprising a lifting lever pivoted to said starting lever for setting in opposite directions into and from effective positions, respectively, and endwise movable in the effective position thereof to lift said starting lever, means operative by the weight of the lap pin thereon to set said lifting lever in effective position, and means on said calender roll operative under rotation of the latter to move said lifting lever in the effective position of said lever, said last means comprising a rotary block on said calender roll, the lifting lever having a hook thereon for engagement by said block.

25 3. In a picker lapping machine, the combination with a vertically swingable starting lever for operating mechanism, a constantly rotating calender roll, and a lap pin, of means to lift said starting lever comprising a lifting lever pivoted to said starting lever for setting in opposite directions into and from effective positions, respectively, and endwise movable in the effective position thereof to lift said starting lever, means operative by the weight of the lap pin thereon to set said lifting lever in effective position, and means on said calender roll operative under rotation of the latter to move said lifting lever in the effective position of said lever, the second mentioned means comprising a yoke forming a seat for said pin and slidably mounted on a fixed part of the machine for downward movement under the weight of said pin therein, and operating connections between said yoke and lifting lever whereby such downward movement of said yoke sets the lifting lever.

40 4. In a picker lapping machine, the combination with a vertically swingable starting lever for operating mechanism, a constantly rotating calender roll, and a lap pin, of means to lift said starting lever comprising a lifting lever pivoted to said starting lever for setting in opposite directions into and from effective positions, respectively, and endwise movable in the effective position thereof to lift said starting lever, means operative by the weight of the lap pin thereon to set said lifting lever in effective position, and means on said calender roll operative under rotation of the latter to move said lifting lever in the effective position of said lever, the second mentioned means comprising a yoke forming a seat for said pin and slidably mounted on a fixed part of the machine for downward movement under the weight of said pin therein, and operating connections between said yoke and lifting lever whereby such downward movement of said yoke sets the lifting lever, said operating connections comprising a bell crank operative by the lifting lever, and a link connection between said bell crank and the lifting lever.

CHRISTIAN A. HUTTO.
